UNITED STATES PATENT OFFICE.

LEO EHRLICH, OF ST. LOUIS, MISSOURI, ASSIGNOR TO THE AMERICAN ROLL PAPER COMPANY, OF SAME PLACE.

PAPER-CUTTER.

SPECIFICATION forming part of Letters Patent No. 393,630, dated November 27, 1888.

Application filed April 23, 1888. Serial No. 271,506. (No model.)

To all whom it may concern:

Be it known that I, LEO EHRLICH, of the city of St. Louis, in the State of Missouri, have invented a certain new and useful Improvement 5 in Paper-Cutters, of which the following is a full, clear, and exact description, reference being had to the accompanying drawings, forming part of this specification, and in which—

Figure I is a front elevation. Fig. II is an 10 end view. Fig. III is an enlarged detail view, and Fig. IV is a similar view showing a modification.

My invention relates to an improvement in 15 paper-cutters; and my invention consists in features of novelty hereinafter fully described, and pointed out in the claims.

Referring to the drawings, 1 represents a suitable base, to which ends 2 are secured.

4 represents the roller journaled in the ends 20 2 and upon which the paper 5 is wound.

6 represents a cross-piece secured to the top of the ends 2, and to the center of which a plate or bracket, 7, is secured at 8. The plate or bracket 7 is made with an opening to receive a rack, 9, having teeth 10, which are engaged by a pawl or dog, 11, to prevent the upward movement of the rack. Secured to the 25 rack is a plate, 13, to the lower end of which a knife, 14, is pivoted by a pin, 15.

30 16 represents a spring secured to the plate 13 at one end and the other end of which bears against the knife 14 to hold it against the roll, as shown in Fig. II. The knife bears upon the roll of paper very nearly on top of the roll, and the result is that the end 17 of the 35 paper is caused to bend upward to give an easy finger-hold when another piece of paper is wanted. As the paper is removed from the roll the knife 14 gravitates and constantly 40 rests upon the roll.

The action of the pawl or dog 11 is to prevent the upward movement of the knife while the paper is being cut off; but it does not act to prevent the downward movement of the knife. This dog is shown disengaged in Fig. 45 III.

In Fig. IV is shown a slight modification, where, instead of the rack 9 having the teeth 10, it is made plain and the dog or pawl 11 is made in the form of a cam. 50

I claim as my invention—

1. In a paper-cutter, the combination of the ends, roller journaled in the ends, plate or keeper secured over the roller, rack working in the plate or keeper, a knife secured to the 55 rack, and a dog or pawl preventing the upward movement of the knife but permitting its downward movement, substantially as and for the purpose set forth.

2. In a paper cutter, the combination of the 60 ends, roller journaled in the ends, gravitating rack supported over the roller plate secured to the rack, knife pivoted to the plate, and a spring bearing on the knife, substantially as and for the purpose set forth. 65

3. In a paper-cutter, the combination of the ends, roller journaled in the ends, cross-bar secured to the ends, keeper secured to the cross-bar and provided with a pivoted dog, rack working in the keeper and provided with 70 teeth engaged by said dog, plate secured to the rack, and a spring-knife secured to the plate, substantially as and for the purpose set forth. 70

LEO EHRLICH.

In presence of—
JOS. WAHLE,
EDWD. S. KNIGHT.
